CATHODE FOR CATHODE RAY TUBE

Hans Otto Roosenstein and Kurt Diels, Berlin, Germany, assignors to Telefunken Gesellschaft für Drahtlose Telegraphie m. b. H., Berlin, Germany, a corporation of Germany

Application March 24, 1937, Serial No. 132,683
In Germany March 24, 1936

5 Claims. (Cl. 250—141)

This invention relates to electron devices, and in particular, to electron emissive cathodes for use in cathode ray apparatus.

Cathode ray devices have suffered in the past from the fact that where the cathode ray beam developed in a cathode ray or Braun tube impacts upon a luminescent surface in a finely focused area, the illumination at the impact surface bounded by the cathode ray beam is not uniform. Accordingly, it is one of the objects of this invention to provide method and means for producing a beam of electrons which, upon impact on a luminescent screen or receiving electrode, shall produce substantially uniform illumination over elemental areas of the impact area.

Other and further objects will become apparent upon the reading of the detailed description taken together with the drawing, in which

Figs. 1a, 1b, 1c show diagrammatically an aperture of a Nipkow disk, graphically the illumination across the disk, and graphically the product of the elemental areas and the intensity of illumination respectively,

Figs. 2a, 2b, and 2c show graphically the impact area of a cathode ray beam, the intensity of illumination across the beam, and the product of elemental zones and intensity of illumination respectively,

Figs. 3a, 3b and 3c show graphically figures similar to those of Figs. 2a, 2b and 2c for another type of cathode ray beam,

Figs. 4a, 4b and 4c show the spot area, the intensity and product of intensity, and elemental areas respectively of an improved cathode ray beam in accordance with the invention,

Fig. 5 shows the pin cushioning effect of a spot area from an uncorrected electronic lens, and

Figs. 6a, 6b, and 6c show modifications for the Figs. 4a, 4b, and 4c; while

Fig. 7c shows a modification of Fig. 6c.

Nipkow disks are known in the prior art in which the holes are of quadratic or rectangular form, with a view to rendering the brightness or luminosity as constant as possible over the width or height of a line or strip in a television frame. Fig. 1a shows a square opening of a Nipkow disk, Fig. 1b the intensity distribution i in the vertical direction of an aperture, and Fig. 1c the brightness distribution h which is also constant in vertical direction, of a line delineated or traced with a Nipkow disk having quadratic openings.

In the case of Braun tubes in which the luminous spot is circular or roughly so, as shown

in Fig. 2a, the distribution of light inside a line, in the direction of its height, is no longer constant, even not in a case where the number of electrons per unit of area of the circular spot is the same. To be sure, along the line marked A—B, the current density is constant as shown in Fig. 2b. The distribution of luminosity, however, is subject to fluctuations in the direction of the height of a strip or line according to a semi-circle as shown in Fig. 2c. The consequence is that in the television picture, even if the lines are directly contiguous, in other words, when they are traced without any intervening spaces, a disturbing structure becomes noticeable in vertical direction, in the presence of zero modulation voltage. In actual practice, the conditions, as a matter of fact, are even still more unsatisfactory than shown in Fig. 2c, for the reason that, because of various factors, the current density throughout the spot is not constant, but decreases somewhat in marginal direction. The current density along line C, D, Fig. 3a has a shape as indicated in Fig. 3b so that the distribution of the intensity over the height of a line has a form as roughly indicated in Fig. 3c.

According to this invention, in order to avoid these disadvantages, the specific electron emission over the area or surface of the cathode is to be chosen in such a way that the distribution of light over the height or width of a line, becomes at least approximately constant. In the case of a distribution of emission along line E—F, Fig. 4a, which is chosen approximately as shown in Fig. 4b, there results again the desired constant distribution as in Fig. 4c.

Presupposing a circular spot, and a roughly undistorting electron-optic lens, then the specific electron emission of the cathode, i. e., the number of electrons emitted per unit area of the cathode, in the presence of constant heating current, can be so chosen that on the line marked E—F, Fig. 4a, the specific emission is variable. The aggregate emission of an area f to the total emission of surface area g must be inversely proportional to length L of area f to the length M of area g . This rule holds good in the case where the fluorescence brightness is proportional to the product of current density and the time during which this current density is acting. If a fluorescent substance is used in which the fluorescence power, similarly as in photographic plates, for the same value of the said product decreases for a shorter time of action, the total emission striking surface f must be still greater than what results from the above rule.

A corresponding distribution of the electron emission throughout the area of a cathode is securable if the cathode surface, prior to its being mounted in a Braun tube, is subjected in an auxiliary device to an electron or ion bombardment across a shiftable slit disposed directly in front of the cathode, and if the length of such treatment of the cathode, and/or the intensity of the bombardment throughout the entire cathode surface is altered in such fashion that the electron emissive substance is partially destroyed.

In order to influence the intrinsic or surface brightness in the direction of the height or width of a line, in the sense of this invention, there could be used such delineation defects as may be present in the electron-optic lens. For example, an electron-optic lens with faulty delineation presenting cushion or pillow shape (with inward bulges or bays), in other words, a lens which produces a spot of the type shown in Fig. 5 from a quadratic cathode may be used under particularly simple conditions. Such an electron-optic lens, when used with a circular lens, would result in a pattern or image that is at least roughly quadratic. Hence, in case of constant current density throughout the entire area of the fluorescent spot, constancy of surface brightness in the direction of the width of a line which is aimed at in the invention, could be attained to a greater degree than with an arrangement Fig. 2.

The requirement of invariable surface brilliance in the width of a line as contained in and solved by the invention could be combined with a further demand, namely, that the surface brilliance should be still constant when the Braun tube, after having been mounted in a television receiver, has been turned while the position of the deflector coils has remained unaltered. Such a turn, as will be noted, may be necessary with a view to compensating inevitable dissymmetries in the construction and mounting of the tube in reference to the terrestrial field or a constant field of the horizontal or vertical deflector coils. If the said additional demand is made, such auxiliary means as have been described in connection with Figs. 4 and 5 as can be readily seen are no longer applicable.

Hence, according to a further object of the invention the specific emissivity over the circular cathode surface is to be chosen in such a way that along each radius of the cathode surface the specific emissivity is made to rise in accordance with the same law in such a way that, for a circular spot, an at least approximately constant brilliance per unit area throughout the width of a strip or line is obtained. A determination of the corresponding electron emission distribution is feasible by analytic and graphic ways and means, whence there results a curve such as shown in Fig. 6b. A graphic determination is readily feasible inside an area amounting to 90 percent of the spot diameter (cross-section), and the same shows that within a distance, which amounts to 5 percent of the diameter the specific emission (or emissivity) must be of unity value (1), while in the middle of the circle it must be 0.21, while intermediately it must be subject to variations as shown. If in each surface element of the spot the emissivity is plotted in the direction of the third coordinate, there results a surface of rotation as will be seen. If the emission is chosen in accordance with Fig. 6b, there ensues again a constant surface brilliance at least inside a stretch equal to 90% of the width or height of a line.

The end aimed at by the invention, namely, to insure a constant surface brilliancy inside the width of a line may be regarded as being obtained under optimum and most favorable conditions when the lines in vertical direction of the television picture are directly contiguous to one another. But in the sense of this invention, also Braun tubes could be used in which the intrinsic or surface brilliancy presents a graphical form inside the width of a line or strip roughly as indicated in Fig. 7c. It can be readily seen that this shape must be obtained if the emission in the direction of the edge of the cathode surface is made to grow still more markedly than shown in Fig. 6b. With such a larger surface brilliancy at the upper and lower edge of the line or strip, even if consecutive lines or strips present a certain spacing or gap, the undesirable structure in the vertical sense of the picture can be caused to disappear to a still greater extent than with an arrangement as shown in Fig. 6.

In what precedes the assumption has been made that the cathode surface itself is imaged upon the fluorescent screen. But in a great many electron-optical arrangements this is true only in this sense that a real image of the cathode produced in the anode diaphragm in turn is thrown upon the fluorescent screen. However, this does not involve any essential change in the conditions such as above outlined seeing that the current density inside a surface element of the real image is proportional to the emissivity of the corresponding surface element of the cathode.

In a finished Braun tube it is feasible to ascertain more exactly whether the brightness distribution throughout the height or width of a line or strip presents a roughly constant shape which is aimed at by this invention, by making the following test: If the defects caused by faulty delineation of the electron-optic lens are not used, a line or strip of enlarged height is thrown upon the fluorescent screen while varying the voltage in the electron-optic lens or varying the current or the position of the focussing coil. By producing such a strip or line on the screen, it will then be easy to ascertain whether the distribution of the surface brilliance according to this invention actually exists. Moreover, by the aid of a photo-optic objective a line or strip of normal delineation could be imaged enlarged and then the distribution of the surface brilliance could be checked up on this image.

What we claim is:

1. A cathode for producing a concentrated beam of electrons in a cathode ray tube comprising a circular planar surface electron emitting element characterized by the fact that the ratio of specific electron emissivity at the peripheral zone on the circular surface bears a ratio of the order of 5 with respect to the specific electron emissivity at the center of the surface.

2. A cathode for producing a concentrated beam of electrons in a cathode ray tube comprising a circular planar surface electron emitting element characterized by a varying specific electron emissivity throughout the area of the element, and further characterized in that the product of the specific electron emissivity of any elemental zone of the element and the area of said elemental zone is substantially equal to the product of the specific electron emissivity of any other elemental zone and the area of that elemental zone.

3. An electron-emitting cathode for producing

a concentrated beam of electrons comprising a planar surface electron emitting element, said element comprising a plurality of contiguous elemental areas arranged according to a predetermined configuration, and each elemental area having different specific electron emissivity from that of contiguous areas.

4. An electron emitting cathode for producing a concentrated beam of electrons comprising a circular planar surface electron emitting element, said element having elemental zonal areas whose specific electron emissivity increases in proportion to the radial distance of the elemental area to the center of the element.

5. An electron emitting cathode for producing a concentrated beam of electrons comprising a circular planar surface electron emitting element, said element having a varying specific electron emissivity over the surface thereof with the specific electron emissivity progressively changing in accordance with the changes in the radial distance from the center to the periphery of the element.
